CLAIM

The ornamental design for an orthopaedic bone plate, as shown.

DESCRIPTION

FIG. 1 is a top perspective view of an orthopaedic bone plate showing the present design.

FIG. 2 is a bottom perspective view thereof.

FIG. 3 is left side elevational view thereof.

FIG. 4 is a right side elevational view thereof.

FIG. 5 is a bottom view thereof.

FIG. 6 is a top view thereof.

FIG. 7 is a front view thereof.

FIG. 8 is a rear view thereof.

FIG. 9 is a top perspective of an alternate embodiment thereof.

FIG. 10 is a bottom perspective view thereof.

FIG. 11 is left side elevational view thereof.

FIG. 12 is a right side elevational view thereof.

FIG. 13 is a bottom view thereof.

FIG. 14 is a top view thereof.

FIG. 15 is a front view thereof; and,

FIG. 16 is a rear view thereof.
